CLAIM

The ornamental design for an archery bow holder, as shown and described.

DESCRIPTION

FIG. 1 is a top plan view of an archery bow holder, showing my new design;

FIG. 2 is a right side elevational view thereof;

FIG. 3 is a bottom plan view thereof;

FIG. 4 is a left side elevational view thereof; and

FIG. 5 is an end elevational view, the opposite end being a mirror image thereof.

FIG. 1

FIG. 2

FIG. 3

FIG. 4

FIG. 5
